UNITED STATES PATENT OFFICE.

GEORGE V. ANDERSON, OF PHILADELPHIA, PENNSYLVANIA.

MACHINE FOR TREATING LEATHER.

1,073,064.

Specification of Letters Patent.

Patented Sept. 9, 1913.

Application filed November 4, 1911. Serial No. 658,480.

To all whom it may concern:

Be it known that I, GEORGE V. ANDERSON, a citizen of the United States, residing in the city and county of Philadelphia, State 5 of Pennsylvania, have invented a new and useful Machine for Treating Leather, of which the following is a specification.

My invention relates to that class of leather-working machines, in which the skin 10 or hide is carried by a traveling bolster to be acted upon by revolving brushes which distribute the seasoning liquid, oil or other liquid upon the skin and rub the same into the skin.

15 To that end my invention consists of a machine in which the skin is carried over a table by means of a traveling bolster or apron and beneath revolving brushes which apply the liquid and rub the same into the skin.

It further consists of feed rollers or pressure rollers which hold the skin against the bolster and are so located between the brushes as to keep the edges of the skin from 25 kicking up or curling under the action of the same.

It further consists of improved means for controlling and regulating the supply of liquid to the skins.

30 It further consists of improved means for removing surplus liquid from the skin.

It further consists of other novel features of construction, all as will be hereinafter fully set forth.

35 The annexed drawings and the following description set forth in detail one mechanical form of embodying the invention, such detail construction being but one of the various mechanical forms in which the principle 40 of the invention may be used.

Figure 1 represents an elevation of the front or receiving side of my improved machine. Fig. 2 represents an elevation of the rear or delivery side of the machine. Fig. 3 45 represents an end elevation of the machine. Fig. 4 represents a somewhat diagrammatic view of the brushes and pressure rollers and the parts immediately coöperating with the same. Fig. 5 represents a view illustrating 50 the driving mechanism for the pressure rollers. Fig. 6 represents a view of portions of the machine at the rear of the machine.

Similar numerals of reference indicate corresponding parts in the figures.

55 Referring to the drawings, the reference numerals 1-1 indicate the end-frames of the

machine, which are suitably connected by braces, 2. A main shaft, 3, is journaled in bearings, 4, in the end-frames, and said shaft has a loose pulley, 5, and a fast pulley, 6, around which a drive-belt (not shown) from a suitable power-supply may pass. The main shaft carries a pinion, 7, which meshes with a transmission-pinion, 8, which in turn meshes with a cog-wheel, 9. A pinion, 10, is secured to revolve with said cog-wheel, and said pinion meshes with a cog-wheel, 11, upon a shaft, 12, having a sprocket-wheel, 13, and journaled in bearings, 14, upon the end-frames. Said shaft 70 also has a drum, 15, and a similar shaft, 16, is journaled at the front of the machine and has a sprocket-wheel, 17, and a drum, 18, of the same diameter as the former drum. A sprocket-chain, 19, passes around the two 75 wheels to drive them and their shafts and drums in unison. The drum-shaft 16 at the front of the machine is journaled in bearings, 20, slideable in arms, 21, and adjustable by means of screws, 22. The arms are fulcrumed at their rear ends upon bolts, 23, in the end-frames, and adjusting-screws, 24, are threaded through lugs, 25, upon the arms and bear with their ends against shoulders, 26, upon the side-frames. The arms are 80 guided by nutted bolts, 27, movable in slots, 28, in the end-frames and may be clamped by said bolts in their adjusted positions. A bolster or endless apron, 29, passes around the drums, and said bolster is preferably 85 formed from sheet-metal. A table, 30, is supported in the frame beneath the upper portion of the bolster upon adjusting-screws, 31, threaded through lugs, 32, upon the end-frames and bearing against brackets, 33, 90 upon the ends of the table, and said bolster has preferably sufficient slack to admit of the table being adjusted above the tangential plane of the drums.

A shaft, 34, is journaled in bearings, 35, upon the upper edges of the side-frames, and has a sprocket-wheel, 36, secured upon one end, over which wheel passes a sprocket-chain, 37, which passes around a sprocket-wheel, 38, upon the main shaft. Said shaft 100 34 carries a cylindrical brush, 39, of sufficient diameter to have the ends of its radiating bristles bear upon the bolster and a skin carried upon the same. The brush-shaft further carries a pinion, 40, which meshes with a pinion, 41, which again meshes with a pinion, 42, of greater diameter than that 105 110

upon the brush-shaft. The shaft, 43, carrying the pinion 42 carries a cylindrical brush, 44, and is journaled in bearings, 45, upon the end-frames. Said pinion 42 meshes with an 5 intermediate pinion, 46, which in turn meshes with a pinion, 47, of larger diameter than the pinion, 42, and carried upon a shaft, 48, journaled in bearings, 49, upon the end-frames and carrying a cylindrical brush, 10 50. The shaft 48 carries a pinion, 51, which meshes with a transmission-pinion, 52, which again meshes with a pinion, 53, carried upon a shaft, 54, journaled in bearings, 55, upon the end-frames and carrying a cylindrical brush, 15 56.

The shaft 34 carries a large pinion, 57, which meshes with a smaller pinion, 58, upon a shaft, 59, journaled in the ends of two links, 60, pivoted upon the shaft 34. 20 Said shaft 59 carries a brush, 61, and the ends of the shaft are guided in suitable slots, 62, in the end-frames. Screw-bolts, 63, are vertically supported upon the end-frames, and pass through slots in the links. 25 Springs, 64, are supported upon said bolts and bear from beneath against the links, tending to raise them, and the tension of said springs may be adjusted by nuts, 65, upon the screw-bolts. Thumb-nuts, 66, 30 upon said bolts and above the links, serve as steps to limit the upward movement of the links. A rock-shaft, 67, is journaled in brackets, 68, upon the end-frames and have cam-arms, 69, bearing from above upon the 35 links to depress them when the shaft is rocked, and the rock-shaft has an arm, 70, to which is pivotally connected a rod, 71, the lower end of which is pivotally connected to a treadle, 72, at the foot of the end-frame. 40

A pinion, 73, is journaled upon a stub-shaft, 74, at the delivery-side of the machine, and meshes with the cog-wheel upon the shaft of the bolster-drum. Said pinion 45 carries a sprocket-pinion, 75, around which passes a sprocket-chain, 76. A shaft, 77, is journaled in bearings upon the end-frames to extend between the brush nearest the feed-side of the machine and the brush next 50 following, and said shaft carries a sprocket-pinion, 78, around which the sprocket-chain, 76 passes. The shaft also carries a series of pressure disks, 79, the peripheries of which bear against the surface of a skin carried 55 beneath them by the bolster. Between the second and the third brush from the feed-side of the machine is journaled another shaft, 80, carrying pressure-disks, 81, and said shaft carries a sprocket-pinion, 81*, en- 60 gaged by the sprocket-chain. At the opposite side of the third brush and at opposite sides of the fourth brush are journaled rollers, 82, in bearings in the end-frames, which rollers are of considerably less diameter than the pressure disks. The rollers are 65

journaled so as to bear against a skin carried by the bolster, and carry sprocket-pinions, 83, meshing with the sprocket-chain. Owing to the fact that the sprocket-pinions on the small rollers have their axes 70 in a plane below that of the axes of the shafts of the larger rollers formed by the pressure disks, two idle sprocket-pinions, 84, and 85, are provided to allow the sprocket-chain to form the required bends 75 from one plane to the other.

A cylindrical tank or reservoir, 86, has trunnions, 87, at its ends, which are journaled to rock in bearings, 88, upon the end-frames, and a bolt 89, sliding in one end-frame engages the tank and retains it in normal position. The tank is formed in its under side with a longitudinal slot, 90, which opens from a rectangular channel, 91, in a longitudinal valve-block, 92, secured in the bottom of the tank. The slot and channel are of the same length as the brushes, and the slot opens down upon the first or feeding brush of the set. A valve, 93, consisting of a flat bar, slides upon the vertical valve-seat formed upon the face of the valve-block, and is held against said seat by the free ends of curved-over springs, 94, secured upon the valve-block. The valve slides over the opening in the valve-seat 95 of the horizontal branch of the rectangular channel to control the outflow of the liquid from the tank, and links, 95, are connected to said valve and pass through the top of the tank, where they are pivotally connected 100 to the ends of arms, 96, upon a rock-shaft, 97, journaled in bearings, 98, upon the top of the tank. An index, 99, is fulcrumed at one end upon an upright, 100, upon the top of the tank, and the free end of such index 105 moves over a graduated scale, 101, likewise upon the tank. A link, 102, is pivoted to the index and to one of the valve-supporting arms, so that the index may be moved with the same when the shaft is rocked to open 110 or close the valve for the outlet. A lever, 103, having a handle, 104, is secured to the rock-shaft, and has a stop-screw, 105, through its rear arm, by means of which the upward throw of the handle, arms and 115 valve may be adjusted. The lever is formed with an opening, 106, in its forward arm, and a rod, 107, passes through said opening and has an adjustable stop-collar, 108, upon its upper end. The lower end of said rod is 120 pivotally connected to one arm of a treadle-lever, 109, the other arm of which forms a foot-treadle, and a belt-shifter, 110, for the driving-pulleys is connected to an upwardly projecting arm, 111, of the lever. Two 125 arms, 112, are pivoted upon the bolster-drum shaft at the rear side of the machine, and the screw-threaded ends of said arms pass through the ends of a bar, 113, and have nuts, 114, by means of which said bar 130

may be adjusted upon said arms. A wiper-strip, 115, of rubber, leather or similar flexible material, is clamped between said bar and a clamping bar, 116, by means of suitable nutted bolts, 117, and the edge of the wiper-strip bears against the bolster across its entire width, so as to remove the seasoning liquor or other liquid from the same. One of the flanges of the bar 113 bears at its ends against seats, 118, upon the end-frames. A pipe, 119, opens from the bottom of the tank and has a cock, 120, for controlling it, and the liquid may be drawn off from the tank through said cock.

In practice, a belt leading from a driving wheel or pulley is slipped upon the loose pulley of the machine, imparting motion to the same. The tank is filled with seasoning liquid or whatever liquid it is desired or required to use, and the stop-screw of the hand-lever is adjusted to admit of the valve-gate being opened to discharge the required quantity of liquid. When now the treadle is depressed, the belt is shifted to the fast pulley and the machine is started, causing the bolster to travel and the brushes to revolve. When a skin is placed in the feed side of the machine upon the bolster, and the hand-lever is thrown up, opening the valve-gate, the bolster will feed the skin through the machine. The liquid running from the tank down upon the first brush will be spread by the latter over the surface of the skin, and be partly rubbed into the same, and the pressure disks and, subsequently, the pressure rollers, together with the traveling bolster will feed the skin toward the rear or discharge side of the machine. With the exception of the last rotary brush, the brushes revolve in a direction to feed the skin toward the discharge side, and the brushes will rub the liquid into the skin. The pressure disks and rollers will keep the skin flat and prevent kicking up or curling of the shanks and flanks of the skins. As described, the brushes rotate with increasing speed toward the discharge side, so that the first brushes will rotate with comparatively slow speed, spreading the liquid, while the subsequent brushes will rub the liquid into the skin. When the skin arrives at the discharge side of the machine, the operator then grasps the skin and depresses the treadle which depresses the last brush into contact with the skin, and said brush, rotating at the highest speed and in a direction opposite to that of the other rolls, will brush any surplus liquid off from the skin before it emerges from the machine, suitable troughs (not shown) being provided to receive and carry away such surplus. The table may be raised or lowered according to the thickness of the skins to be treated and the pressure to be exerted upon them. When a skin has passed through the ma-

chine, the treadle at the feed-side is released, throwing the belt onto the loose pulley, and the rod connected to the treadle will draw the hand-lever upon the reservoir down, closing the gate-valve. Whatever liquid flows onto the traveling bolster will be scraped off by the scraper at the discharge-side, so that the under side of the next skin passing through the machine will not be stained or otherwise affected by any liquid remaining on the bolster. The tank may be emptied through the pipe in the bottom of the same, and may be cleaned by withdrawing the bolt and tilting the tank so that the valve, valve-block and passages through the same may be conveniently and thoroughly washed out. The rod-connection between the valve-actuating hand-lever and the treadle, consisting of the rod connected to the foot treadle and passing through the opening in the lever, having the collar at its upper end, will cause said rod to drop when the treadle is released and the belt shifted to the loose pulley and carry the lever down to close the gate-valve and stop the flow of liquid, while depressing of the treadle to start the machine will merely raise the rod, whereupon the hand-lever may be raised by hand to open the valve, so that stopping of the machine shuts off the flow of liquid, while the flow will not be started until after the machine has been started and the skin fed to the machine. By this provision, the liquid will not waste upon the bolster, but will only flow when a skin is in the machine. The degree of opening of the valve may be adjusted by the stop-screw and may be read upon the scale from the position of the index.

The table beneath the traveling bolster affords a level and solid support for the entire skin, so as to admit of the same being presented perfectly smooth and even to the rubbing action of the brushes. The table may be adjusted in its relation to the brushes and pressure disks and rollers according to the thickness of the skins to be treated and the desired degree of rubbing by the former and pressure by the latter. The disks and rollers will have a stretching effect upon the skins besides feeding them, and the rollers, bearing completely across the skins, will keep the same flat upon the bolster and table against the kicking-up or curling action of the revolving brushes. If desired, the machine may be provided with a full set of pressure rollers instead of the shafts and pressure disks.

Other modes of applying the principles of my invention may be applied for the mode herein explained. Change may therefore be made as regards the mechanism herein disclosed, provided the principles of construction set forth respectively in the following claims are employed.

Having thus described my invention, what I claim as new and desire to secure by Letters Patent, is:—

1. In a machine of the character stated, a traveling bolster, a series of parallel rotatable brushes arranged to act against said bolster, means for revolving said brushes at progressively increasing speeds to feed in the direction of the travel of the bolster, a brush rotatably mounted at the discharge side of the machine and parallel to said former brushes, and means for revolving said latter brush in a direction opposite to that of said former brushes. 70
2. In a machine of the character stated, a traveling bolster, a series of parallel rotatable brushes arranged to act against said bolster, means for revolving said brushes at progressively increasing speeds to feed in the direction of the travel of the bolster, a brush rotatably mounted at the discharge side of the machine and parallel to said former brushes, means for revolving said latter brush in a direction opposite to that of said former brushes. 75
3. In a machine of the character stated, a pair of parallel drums, an endless bolster carried around said drums, means for rotating said drums, a table arranged between said drums to have said bolster travel over it, a series of parallel rotatable brushes acting against said bolster and table, means for revolving said brushes at progressively increasing speed, a brush rotatably mounted at the discharge side of the machine, means for revolving said brush in a direction opposite that of the former brushes, pressure rollers journaled between the brushes to act against the bolster and table, and means for revolving said rollers. 80
4. In a machine of the character stated, a pair of parallel drums, an endless bolster carried around said drums, means for rotating said drums, a table arranged between said drums to have said bolster travel over it, means for adjusting the level of said table, a series of parallel rotatable brushes acting against said bolster and table, means for revolving said brushes at progressively increasing speed, a brush rotatably mounted at the discharge side of the machine, means for revolving said brush in a direction opposite that of the former brushes, pressure rollers journaled between the brushes to act against the bolster and table, and means for revolving said rollers. 85
5. In a machine of the character stated, a pair of parallel drums, an endless bolster carried around said drums, means for rotating said drums, a table arranged between said drums to have said bolster travel over it, a series of parallel rotatable brushes acting against said bolster and table, means for revolving said brushes at progressively increasing speeds to feed in the direction of the travel of the bolster, a brush rotatably mounted at the discharge side of the machine, means for revolving said brush in a direction opposite that of the former brushes, means for moving said brush toward and from said bolster and table, pressure rollers journaled between the brushes to act against the bolster and table, and means for revolving said rollers. 90
6. In a machine of the character stated, a pair of parallel drums, an endless bolster carried around said drums, means for rotating said drums, a table arranged between said drums to have said bolster travel over it, means for adjusting the level of said table, a series of parallel rotatable brushes acting against said bolster and table, means for revolving said brushes at progressively increasing speed, a brush rotatably mounted at the discharge side of the machine, means for revolving said brush in a direction opposite that of the former brushes, means for moving said brush toward and from said bolster and table, pressure rollers journaled between the brushes to act against the bolster and table, and means for revolving said rollers. 95
7. In a machine of the character stated, a traveling bolster, a series of parallel rotatable brushes arranged to act against said bolster, a tank having a discharge-opening above the first brush of the series, means for revolving said brushes at progressively increasing speeds to feed in the direction of the travel of the bolster, a brush rotatably mounted at the discharge side of the machine and parallel to said former brushes, and means for revolving said latter brush in a direction opposite to that of said former brushes. 100
8. In a machine of the character stated, a traveling bolster, a series of parallel rotatable brushes arranged to act against said bolster, a tank having a discharge-opening above the first brush of the series, means for revolving said brushes at progressively increasing speeds to feed in the direction of the travel of the bolster, a brush rotatably mounted at the discharge side of the machine and parallel to said former brushes, means for revolving said latter brush in a direction opposite to that of said former brushes, and means for moving said latter brush toward and from the bolster. 110
9. In a machine of the character stated, a pair of parallel drums, an endless bolster carried around said drums, means for rotating said drums, a table arranged between said drums to have said bolster travel over it, a series of parallel rotatable brushes acting against said bolster and table, a tank having a discharge-opening above the first brush of the series, means for revolving said brushes at progressively increasing speed, 115
10. In a machine of the character stated, a pair of parallel drums, an endless bolster carried around said drums, means for rotating said drums, a table arranged between said drums to have said bolster travel over it, a series of parallel rotatable brushes acting against said bolster and table, means for revolving said brushes at progressively increasing speed, 120
11. In a machine of the character stated, a pair of parallel drums, an endless bolster carried around said drums, means for rotating said drums, a table arranged between said drums to have said bolster travel over it, a series of parallel rotatable brushes acting against said bolster and table, a tank having a discharge-opening above the first brush of the series, means for revolving said brushes at progressively increasing speed, 125
12. In a machine of the character stated, a pair of parallel drums, an endless bolster carried around said drums, means for rotating said drums, a table arranged between said drums to have said bolster travel over it, a series of parallel rotatable brushes acting against said bolster and table, means for revolving said brushes at progressively increasing speed, 130

a brush rotatably mounted at the discharge side of the machine, means for revolving said brush in a direction opposite that of the former brushes, pressure rollers journaled between the brushes to act against the bolster and table, and means for revolving said rollers.

10. In a machine of the character stated, a pair of parallel drums, an endless bolster carried around said drums, means for rotating said drums, a table arranged between said drums, to have said bolster travel over it, means for adjusting the level of said table, a series of parallel rotatable brushes acting against said bolster and table, a tank having a discharge-opening above the first brush of the series, means for revolving said brushes at progressively increasing speed, a brush rotatably mounted at the discharge side of the machine, means for revolving said brush in a direction opposite that of the former brushes, pressure rollers journaled between the brushes to act against the bolster and table, and means for revolving said rollers.

11. In a machine of the character stated, a pair of parallel drums, an endless bolster carried around said drums, means for rotating said drums, a table arranged between said drums to have said bolster travel over it, a series of parallel rotatable brushes acting against said bolster and table, a tank having a discharge-opening above the first brush of the series, means for revolving said brushes at progressively increasing speed, a brush rotatably mounted at the discharge side of the machine, means for revolving said brush in a direction opposite that of the former brushes, means for moving said brush toward and from said bolster and table, pressure rollers journaled between the

brushes to act against the bolster and table, and means for revolving said rollers.

12. In a machine of the character stated, a pair of parallel drums, an endless bolster carried around said drums, means for rotating said drums, a table arranged between said drums to have said bolster travel over it, means for adjusting the level of said table, a series of parallel rotatable brushes acting against said bolster and table, a tank having a discharge-opening above the first brush of the series, means for revolving said brushes at progressively increasing speed, a brush rotatably mounted at the discharge side of the machine, means for revolving said brush in a direction opposite that of the former brushes, means for moving said brush toward and from said bolster and table, pressure rollers journaled between the brushes to act against the bolster and table, and means for revolving said rollers.

13. In a machine of the character stated, a tank, a valve-block in the bottom of the tank, a gate-valve sliding upon the face of said block to control the passage in the same, a rock-shaft upon the tank, means connecting said rock-shaft and valve to open and close the same as the shaft is rocked, a hand-lever upon the rock-shaft to rock the same and formed with an opening, a treadle connected to start and stop the machine, and a rod through the opening in the hand-lever and provided with a stop-collar at its upper end and connected to the treadle at its lower end.
